[57] CLAIM

The ornamental design for telephone trays, tool caddies, or similar articles, as shown and described.

DESCRIPTION

FIG. 1 is a right side, top and front end perspective view of a support for telephone trays, tool caddies, or similar articles showing our new design;

FIG. 2 is a right side elevational view thereof, the side opposite being a mirror image;

FIG. 3 is a front elevational view thereof;

FIG. 4 is a top plan view thereof; and

FIG. 5 is a right side, top and front perspective view thereof showing the sliding arm of the support in its extended position.

FIG. 1

FIG. 2

FIG. 3

FIG. 4
